US0D1062722S

(12) **United States Design Patent** (10) **Patent No.:** **US D1,062,722 S**
(45) **Date of Patent:** **** Feb. 18, 2025**

(54) **STAND FOR MOBILE DEVICE OR COMPUTER**

(71) Applicants: **DONGGUAN SOLUTION 33 ELECTRONIC TECHNOLOGY CO., LTD.**, Dongguan (CN); **SOLUTION EXPERT 33 INTERNATIONAL CO., LTD.**, Tortola (VG); **SOLUTION EXPERT 33 INTERNATIONAL CO., LTD. TAIWAN BRANCH**, New Taipei (TW); **SENSEAGE CO., LTD.**, Taipei (TW)

(72) Inventor: **Ben-Tien Lin**, New Taipei (TW)

(73) Assignees: **DONGGUAN SOLUTION 33 ELECTRONIC TECHNOLOGY CO., LTD.**, Dongguan (CN); **SOLUTION EXPERT 33 INTERNATIONAL CO., LTD.**, Tortola (VG); **SOLUTION EXPERT 33 INTERNATIONAL CO., LTD. TAIWAN BRANCH**, New Taipei (TW); **SENSEAGE CO., LTD.**, Taipei (TW)

(**) Term: **15 Years**

(21) Appl. No.: **29/773,153**

(22) Filed: **Mar. 8, 2021**

(30) **Foreign Application Priority Data**

Nov. 12, 2020 (CN) 202030684744.6

(51) **LOC (15) Cl.** **14-03**

(52) **U.S. Cl.**

USPC **D14/253; D14/447**

(58) **Field of Classification Search**

USPC D14/251-253, 447, 440; D3/218

CPC H04M 1/04; H04M 1/12

See application file for complete search history.

(57) **CLAIM**

The ornamental design for a stand for mobile device or computer, as shown and described.

DESCRIPTION

FIG. 1 is a front perspective view of a stand for mobile device or computer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the stand for mobile device or computer of FIG. 1 shown in an alternate position; and,

FIG. 9 is a front perspective view of the stand for mobile device or computer of FIG. 1 shown in a position of use with a mobile device.

The broken lines in FIG. 9 illustrate environmental subject matter and form no part of the claimed design.

1 Claim, 7 Drawing Sheets
